UNITED STATES PATENT OFFICE.

FREDERICK FOURNIER, OF SAN FRANCISCO, CALIFORNIA.

WINDOW FASTENER OR LATCH.

1,427,730.

Specification of Letters Patent. Patented Aug. 29, 1922.

Application filed February 25, 1920. Serial No. 361,127.

To all whom it may concern:

Be it known that I, FREDERICK FOURNIER, a citizen of the United States, residing at city and county of San Francisco and State 5 of California, have invented a new and useful Improvement in Window Fasteners or Latches, of which the following is a specification.

This invention relates to window fasteners 10 or latches.

It is the principal object of the present invention to provide a simple and efficient form of window fastener, especially adaptable for use in connection with swinging windows to 15 securely lock the same in their closed position.

The present invention contemplates the mounting of an eccentric actuated latch finger on the window casing, which finger is 20 adapted, when actuated, to engage a keeper plate on the window sash to draw the latter securely against and secure it to the casing.

One form which the invention may assume 25 is exemplified in the following description and illustrated in the accompanying drawings, in which:

Fig. 1 is a fragmentary view in perspective illustrating the manner in which the latch is applied to a swinging window casing.

Fig. 2 is an enlarged view illustrating the latch mechanism.

Referring more particularly to the drawings, 10 indicates a sash frame provided with a swinging sash 11 and a latch mechanism 35 generally indicated at 12, the latter forming the subject matter of the present invention. The latch consists of a keeper plate 31 which is secured to the inner face of the sash stile. This plate is formed with a vertically ex- 40 tending rectangular slot 32 into which a lock finger 33 may project. The lock finger 33 is pivotally or freely mounted upon an operating eccentric 34. This eccentric is circular and seats within a circular opening 45 formed through the finger. A pivot pin 35 extends through the eccentric at a point off center and thus insures that as an operator 36 is swung the finger 33 will be advanced or retracted as the case may be, it being understood that the lock finger is positively 50 secured to move with the eccentric 34. The finger 33 has a hooked end 37 upon the outer face of which a protrusion 38 occurs. This protrusion is adapted to register with a recess 39 in the back of the keeper plate 32 to prevent the finger from being pried up when

the window is locked. It will also be noted that the finger has an oscillating movement as well as a reciprocating movement. This is produced by a lug 40 in the path of travel 60 of the enlarged pivotal end of the finger. This lug engages a cam face 41 along the under side of the finger and when the finger is in its forward position will act to elevate the finger while permitting it to fall as the 65 eccentric is rotated and the latch finger retracted.

In operation of the present invention it will be assumed that the window is in its closed position and the latch retracted. To 70 latch the window the operating arm 36 is rotated to rotate the eccentric 34. This elevates and advances the latch finger 33 to engage the keeper plate. During the latter part of the eccentric's action, the finger 33 is 75 lowered and slightly retracted so as to engage the protrusion 38 with the recess 39 and also draw the window tightly against the sash frame.

It will thus be seen that the device here 80 disclosed provides a simple form of latch which will draw the sash tightly against the casing and secure it there.

While I have shown the preferred form of my invention as now known to me, it 85 will be understood that various changes in the construction, combination and arrangement of the various parts employed may be made by those skilled in the art without departing from the spirit of the invention as 90 claimed.

Having thus described my invention, what I claim and desire to secure by Letters Patent, is:—

1. A latch structure comprising a lock 95 plate, a keeper plate disposed in a plane at right angles thereto, and having an opening therethrough, a circular lock cam eccentrically pivoted upon the lock plate and swinging in a plane parallel thereto, a lever mem- 100 ber for rotating said cam, a lock finger having a circular opening through which the cam extends, said finger moving in a plane parallel to the face of the lock plate and adapted to project through the opening in 105 the keeper plate, a downwardly extending hook formed at the outer end of said frame, a wedge face formed on the lower edge of the finger near its pivotal mounting, and a lug on the lock plate, cooperating with the 110 eccentric movement of the lock cam, where- by rotation of said cam will cause the hooked

end of the finger to move upwardly and forwardly through the opening in the keeper plate, thereafter lowering until its hooked end engages the keeper plate, and then drawing toward the lock plate.

2. A latch structure comprising a lock plate, a keeper plate disposed in a plane at right angles thereto, and having an opening therethrough, a circular lock cam eccentrically pivoted upon the lock plate and swinging in a plane parallel thereto, a lever member for rotating said cam, a lock finger having a circular opening through which the cam extends, said finger moving in a plane parallel to the face of the lock plate and adapted to project through the opening in the keeper plate, a downwardly extending hook formed at the outer end of said frame, a wedge face formed on the lower edge of the finger near its pivotal mounting, and a lug on the keeper

plate, cooperating with the eccentric movement of the lock cam, whereby rotation of said cam will cause the hooked end of the finger to move upwardly and forwardly through the opening in the keeper plate, 25 thereafter lowering until its hooked end engages the keeper plate, and then drawing toward the lock plate, a retaining lug formed on the end face of the lock finger hook and a protrusion on the keeper plate beneath which said lug seats when the finger is drawn thereagainst.

In testimony whereof I have hereunto set my hand in the presence of two subscribing witnesses.

FREDERICK FOURNIER.
